UNITED STATES PATENT OFFICE.

LEVIN H. MULLIKIN, OF TRAPPE, MARYLAND.

COMBINED LOCK AND LATCH.

SPECIFICATION forming part of Letters Patent No. 697,156, dated April 8, 1902.

Application filed August 27, 1901. Serial No. 73,472. (No model.)

To all whom it may concern:

Be it known that I, LEVIN H. MULLIKIN, a citizen of the United States, residing at Trappe, Talbot county, Maryland, have invented certain new and useful Improvements in a Combined Lock and Latch, of which the following is a specification.

My invention relates that class of locks and latches shown in my Patent No. 646,094, dated March 27, 1900, in which a knob-operated latch is held in its thrown position against retraction by means of a rotary tumbler or disk which can only be operated by a suitable key.

The object of the invention is to improve the construction of the locking-tumbler by providing it with notches having one wall rounded or inclined to throw out the nose of the locking-dog and having the other wall abrupt to prevent further rotation of the tumbler and stop it at the moment the nose of the dog enters either notch, and so insure the tumbler always stopping at the nose of the dog instead of being sometimes carried past it.

A further object is to provide the locking-dog with guide-arms to engage the upper and lower walls of the lock-case and to prevent canting or rocking of said dog.

These objects I attain by the mechanism illustrated in the accompanying drawings, in which—

Figure 1 is a plan of the cylindrical lock with one of its casing-sections or cover removed and the tumbler turned so as to allow the retraction of the latch, as shown in dotted lines. Fig. 2 is a similar view with the tumbler or locking-disk turned so as to lock the latch against retraction. Fig. 3 shows the dog for locking or retaining the tumbler or disk in position. Fig. 4 is a detail perspective of the said tumbler or disk. Fig. 5 is a plan of the latch, the locking-tumbler, and the tumbler-retaining dog from the side opposite to that shown in Fig. 1. Fig. 6 is an edge view of the latch and the tumbler-retaining dog. Fig. 7 is a side elevation of the key.

A represents a cylindrical lock-case, adapted to enter a hole bored by an auger and formed in two longitudinal sections a' , secured together by a screw a^2 , the section a being provided at its front end with a face or attaching plate a^3 .

B is the latch, having the usual beveled nose

at its formed end, an open middle portion b , connected to the nose by a reduced member or shank b' and having a yoke b^2 at its rear and engaged by the two-armed sleeve c of the knob-spindle C for retraction thereby in the usual manner.

Upon the inner end of the latch-shank b' is loosely placed the apertured bearing-plate D, having a lug d and guide-arms d^2 projecting rearwardly from one edge, the said plate and its arms and lug constituting the retaining-dog for the locking tumbler or disk E. The arms d^2 prevent the bearing-plate from canting and binding against the upper and lower walls of the lock-case. The plate D is further held in its proper position by means of opposed recesses d^1 , formed in the inner side walls of the lock-case.

F is the latch-projecting spring, mounted on the shank b' and bearing at one end on the rear end of the nose of the latch and at its rear end bearing against the plate D.

The tumbler or disk E is formed with two hubs or trunnions e , seated in recesses e' in the inner faces of the lock-case, and these recesses are intersected by the two keyholes e^2 in the lock-case. The tumbler or disk E has a keyhole or slit e^3 extending through it and its hubs, and in order that these keyholes $e^2 e^3$ may always register for the removal and insertion of a key E', I provide the tumbler or disk with two notches or recesses $e^5 e^6$, into which the lug or toe d of the locking-dog snaps when the disk or tumbler is in its locking and inoperative positions. These recesses in my patented construction were beveled on both sides, and so it was possible to turn the tumbler a full revolution, which was found to be objectionable, for the reason that the notches were then carried past the lug d . I now bevel or round one wall only of each recess e^5 and make the other wall abrupt, so as to form shoulders e^7 , which will engage the lug d and always hold the tumbler or disk E from further rotation whenever the lug d snaps into one of the notches. Thus the proper position of the said tumbler or disk is positively insured without the necessity of the operator listening to ascertain whether or not the dog had snapped into a notch.

The latch B is cut away at the opposite sides of its open middle portion, as at b^5 , so as to

overlie the tumbler or disk E and slide rearwardly over it when it is in the position shown in Fig. 1, and the said tumbler or disk is provided with a raised rib or projection e^6 , adapted to rest behind shoulders $b^6 b^6$, formed by the forward ends of the cut-away portions b^5 , and so prevent the retraction of the latch, as best shown in Fig. 2.

When the parts are in the position shown in Fig. 1, the latch operates in the usual manner upon turning the knob-spindle; but when it is desired to lock the latch against retraction the key is inserted from either side of a door into the tumbler or disk and then turned to rotate said tumbler and bring its rib or projection e^6 against the shoulders b^6 . In thus rotating the tumbler or disk the beveled walls of its notches e^5 will cause the toe or lug d of the retaining-dog to be forced away against the action of spring F, as shown in dotted lines, Fig. 1, until the opposite notch or recess reaches the toe or lug, whereupon the disk or tumbler will be prevented from turning farther and the said toe will snap therein and hold the disk or tumbler with its keyhole in register with the casing-keyhole.

The combined lock and latch may be applied without the necessity for skilled labor, as it is only necessary to have an auger of the proper size and bore a round hole to receive the cylindrical lock-case. The parts are few and not liable to get out of order.

Having thus described my invention, what I claim as new, and desire to secure by Letters Patent, is—

1. A combined lock and latch, comprising a latch having an open middle portion, means for retracting and projecting the latch, a rotary key-operated locking-disk underlying the middle open portion of the latch and provided with a raised rib or projection adapted upon the rotation of said disk to rest against the forward end of said open portion of the latch and prevent its retraction, and said disk having notches at opposite points in its periph-

ery, one wall of each notch being beveled or rounded and the other being abrupt to form a shoulder to prevent further rotation of the disk, a retaining-dog comprising a spring-pressed apertured plate provided with a toe or lug to snap into and be forced out of said peripheral notches by the inclined walls thereof upon the rotation of the locking-disk, substantially as set forth.

2. A combined lock and latch, consisting in the divided cylindrical casing having recesses in its inner walls near its forward end, keyholes in rear thereof, bearings at the inner sides of the casing intersected by said keyholes and bearings at its rear end, a latch mounted in said casing and having a middle open portion, a forward shank and a yoke at its rear end, a knob-spindle sleeve mounted in the rear bearings to retract the latch, a spring on the shank to project the latch, a locking-disk having hubs turning in the middle bearings, a keyhole extending through the disk and its hubs to register with the casing-keyholes, and peripheral notches in its periphery and on a line at right angles to its key-hole, one wall of each notch being rounded or beveled and the other abrupt to form a shoulder to prevent further rotation of the disk, and a retaining-dog for the disk, comprising an apertured plate mounted on the shank in rear of the spring with its side edges in the forward recesses of the casing and provided with a toe or lug to snap into and be moved out of the said notches by the beveled walls thereof upon the rotation of the disk; and also having upper and lower guide-arms e^7 engaging the upper and lower walls of the lock-case; substantially as described.

In testimony whereof I affix my signature in presence of two witnesses.

LEVIN H. MULLIKIN.
